UNITED STATES PATENT OFFICE.

CHESTER S. JENNINGS, OF BOSTON, MASSACHUSETTS, ASSIGNOR TO THE LAMSON COMPANY, OF BOSTON, MASSACHUSETTS, A CORPORATION OF NEW JERSEY.

TWIST-BELT CONVEYER FOR NEWSPAPERS AND THE LIKE.

1,332,900.

Specification of Letters Patent.

Patented Mar. 9, 1920.

Application filed August 22, 1916. Serial No. 116,265.

To all whom it may concern:

Be it known that I, CHESTER S. JENNINGS, a citizen of the United States, residing at Forest Hills, Boston, in the county of Suffolk 5 and State of Massachusetts, have invented certain new and useful Improvements in Twist-Belt Conveyers for Newspapers and the like, of which the following is a specification.

10 This invention relates to belt conveyers for newspapers and the like and more especially to novel conveyers of this general description in which during the translation of articles, by a part of said conveyer, upwardly or downwardly as the case may be, there is also imparted to said articles a rotary motion about a more or less vertical line of travel, to the end that said articles may be laterally delivered from the elevator 15 20 whether traveling up or down in a line extending, for example, at an angle of 90° to the line in which they were introduced into said elevator; said lines being of course not only in different horizontal planes or levels but also in different vertical planes, preferably planes intersecting along and corresponding to the axis of rotation about which said articles are turned during their conveyance between the different levels.

25 30 To provide means therefore whereby articles may thus be angularly turned during their translation along a given path and to effect this angular motion of said articles without injury to said articles are among the principal objects of the present invention.

Another object of my invention is to so 35 constitute the respective elements of the preferred embodiment thereof as to avoid the provision of a multiplicity of differently 40 formed bearings and the like, while fitting certain of said elements for ready adjustment with respect to each other to adapt them for expeditious assembly.

45 These and other objects of said invention will be hereinafter referred to and the novel combinations of elements and means whereby said objects may be attained will be more particularly pointed out in the claims appended hereto.

50 In the drawings which form a part hereof and in which like reference characters designate like parts throughout the several views,

I have exemplified a preferred construction; but as I am aware of various changes and 55 modifications which may be made herein without departing from the spirit of my invention, I desire to be limited only by the scope of said claims.

Referring to the drawings:

60 Figure 1 is a side elevation of a newspaper conveyer constructed in accordance with the principles of my invention.

Fig. 2 is a transverse section, drawn to an enlarged scale; the section being taken on 65 the line II—II of Fig. 1.

Fig. 3 is a detail plan view, drawn to a scale corresponding to that used for Fig. 2, and showing the obliquely extending delivery end of the conveyer.

70 Fig. 4 is a detail end view of one of the bearings which support the angularly disposed rolls.

Fig. 5 is a fragmentary section taken on line V—V of Fig. 4 and showing said bearing in side elevation.

Fig. 6 is a side view of a fragment of my novel twist-belt, showing the same in position on a roller a portion of which has been broken away for purposes of illustration.

80 Fig. 7 is a fragmentary detail section of said belt, the section being taken on line VII—VII of Fig. 6; and

Fig. 8 is a bottom view of a fragment of the belt shown in Fig. 6.

85 The construction given by way of exemplification comprises a horizontal run of belting composed of narrow belts 1 which pass around pulleys 2 and 3 at the respective ends thereof. The shafts 4 and 5 upon which these pulleys are mounted are driven in synchronism by means of chain and sprocket connections; the shaft 4 preferably driving the shaft 5 in the direction indicated by the arrows.

90 To avoid confusion, in the principal view, Fig. 1, I have indicated such chain and sprocket drives as this, wherever they occur by dash and dotted lines. Thus, the sprockets mounted upon the shaft 5, by means of which this shaft is driven, have been designated 6 and the chains corresponding thereto 7; while the driving sprocket on the shaft 4 has been designated 8.

95 The horizontal belts 1 are supported beneath their carrying surfaces by rollers 9

and the papers are delivered to these belts by a "fly" 10 such as is provided in connection with many printing-presses in common use.

5 The papers in overlapped relationship are delivered from the belts 1 to what are known as angle belts 11, which may be arranged with respect to the belts 1 as indicated in Fig. 2.

10 I make no claim herein to these angle belts, which may hence be of any suitable character but which are preferably mounted on pulleys 12, 13 and 14, as shown in Figs. 1 and 2. The pulleys 14 are mounted upon a 15 shaft 15 carried by pivoted arms 16 to the end that said pulleys 14 may tension the angle belts. The arms 16 may be pivoted as at 17 to brackets 18 attached to the uprights 19, which as shown in Fig. 2 may be channeled.

15 The uprights or channels 19 preferably do not extend all the way from the bottom to the top of the elevator; but preferably have attached to their upper extremities a substantially circular band 20, while a short 20 distance below this band is a second and similar band 21 which is shown in plan in Fig. 2.

25 A second set of upright channels 22 extends up from the lower band 21 and is secured to this latter and to the band 20; but it will be observed that the channels 22 are angularly spaced around upon their supporting bands, each at some distance from the corresponding lower upright 19.

30 In this convenient fashion, what I may term a twist-frame is provided, in which the relative lengths of the respective upper and lower uprights in view of the total amount 35 of twist in the conveyer, will determine the angular displacement of the uprights 22 with respect to those designated 19. In the present case, the total twist is approximately 45°.

40 The uprights 22 may be connected at their upper extremities by a cross-bar or channel 23, as shown in Figs. 1 and 3; a portion of channel 23 being broken away in the latter figure to better show the belt connections.

45 Laterally projecting toward one side or another of the respective uprights 19 and 22, arcuate bearing plates 24 are provided at any desired different levels, to carry the bearing brackets 25 in which are received 50 the journals 26 in which ride the trunnions or shafts 27 of the respective guide rolls 28.

55 The plates 24 are spaced inwardly from the upright channel and are securely attached to the latter by bracket-plates 29, as 60 shown in Fig. 2; and the provision of these arcuate plates as a means of support for the roll bearings is of particular advantage in that it greatly facilitates the erection of the elevator; the frame of the latter being assembled and the arcuate plates attached

thereto, after which the various bearing brackets 25 with their journals 26 and rolls 28 are mounted approximately in position upon said plates 24. The shafts 27 are thus supported in different vertical planes at 70 their different levels, and then the rolls and their bearings and brackets are adjusted angularly with respect to each other, as best shown in Fig. 2, until they have been properly lined up. The brackets 25 may then be 75 secured in place by means of bolts 29' or the like; one bolt sufficing for each bearing bracket. As shown in Fig. 5, each of these brackets are preferably provided with a depending flange 25' upon their inner side, 80 through which the corresponding bolt 29 may be passed; while this flange is turned laterally and then downwardly to afford a recess for the upper edge of the plate 24 to which it is attached, so that this edge is, in 85 effect, embraced by the bracket to afford a secure connection therewith.

85 The journals 26 are provided with laterally extending lugs 26' which are received into V-shaped cuts or recesses in the sides of 90 the brackets; this arrangement permitting of a rocking movement of each journal with respect to its bracket, since the aperture in the bracket which receives the journal is of somewhat larger diameter to afford an angular space therebetween. As a result of 95 this, the rolls may be canted or slewed around with respect to their supporting journal brackets, through a considerable angle; the uppermost roll 28, Fig. 2, for instance, is shown thus disposed with respect to one of its brackets 25, in said figure.

100 Each of the guide rolls 28 is provided with grooves 28', which as shown in Fig. 7, preferably flare outwardly, so that in cross section they are substantially trapezoidal, to favor the reception thereinto of spaced guiding projections or lugs upon the belts which ride thereover.

105 These belts, which are the main elevating belts, have been designated 30 or 30', as the case may be, and may be of leather or the like and preferably have secured to their pulley-contacting surfaces, guide-projections 31, which as shown in Fig. 6, may be conveniently made by riveting together and to the belt 30 or 30' to which they are attached, for example, two thicknesses of leather belting cut in blocks, so that when assembled 110 the edges of a given projection thus formed, 115 which extend lengthwise of the belt, taper inwardly toward each other in correspondence with the tapering sides of the grooves 28' into which they are received. The formation of the transverse edges of these 120 blocks is not so important, but they are preferably shaped as shown in Fig. 6, to facilitate passage of the belt around pulleys of relatively small radius, as indicated by dash and dotted lines in said figure. Indeed, 125 130

by means of this construction, the belt retains substantially all of its flexibility and may readily be passed around pulleys of, for example, six inches in diameter, while 5 by reason of these projections and of the grooves in the pulleys, the belts where engaged with the pulleys, are at all times definitely positioned thereon. A further and more important advantage resulting 10 from this provision will be hereinafter discussed.

The belts 30—30' are preferably arranged in sets; there being in the present case three belts in each set.

15 The respective sets of belts move in the direction of the arrows indicated adjacent thereto and since the construction given by way of exemplification is intended to elevate the newspapers from one level to another, 20 the opposed sides of the respective belts 30—30' move upwardly together, preferably slightly zig-zag between the pulleys 28, with their fronts or projection-free faces in contact with the papers against which said 25 faces are passed. The guide and pressure rolls 28 are preferably arranged in staggered relationship from top to bottom of the elevator and as the article-conveying portions of the belts 30—30' pass up between 30 these staggered rolls, said belts will also be rotated or twisted angularly, owing to the angular shift of the axis of each roll with respect to the axis of the roll immediately therebelow.

35 The article-carrying run of each of the belts 30 passes around a pulley 32, of which of course there are three, mounted on a shaft 33. Thereafter the three belts 30 run downwardly toward and pass around the corresponding pulleys 34 mounted on the shaft 40 at the lower end of the elevator. Correspondingly, the belts 30', when they reach the limit of their upward travel, pass around pulleys 36, mounted on a shaft 37, adjacent 45 the cross-bar 23; and said belts thereafter descend, as indicated in Fig. 1, toward and around the pulleys 38, mounted on the shaft 5, above referred to. The descending limbs of the belts 30—30' are held against lateral 50 vibration by guide or idler pulleys 39, mounted upon brackets 40, which as shown in Fig. 2, are pivotally connected at 41 to their bases 40' to permit of adjustment of the pulleys 39 with reference to the respective channels 22, to which said bases 40' are attached. It will be understood of course that after a given pulley bearing 40 has once been positioned with respect to its corresponding bracket-base 40', it is made fast 55 in any suitable fashion to prevent the tension of the belt rotating it inadvertently about its pivotal axis 41.

Belt tighteners are also provided for the respective belts 30—30', these tighteners each 60 comprising a pair of shafts 42, the ends of

which are mounted in rocker frames 43, which are pivotally attached to cross-bars 44 as at 45. These frames 43 are each provided with a spring 46 which tends to rock its corresponding frame so as to swing the upper shaft 42 of such frame outwardly and the lower shaft inwardly.

The inwardly moving or lower shaft 42 of each tensioning device carries smooth-faced pulleys or idlers 47, while the corresponding upper shaft carries grooved pulleys 48; the outer or smooth side of the belts 75 engaging the pulleys 47 and the projections 31 riding in the grooves of the pulleys 48.

At the top of the elevator are two angle 80 belts 49 which pass around pulleys 50 mounted on the shaft 37, pulleys 51 mounted on a shaft 52, and pulleys 53 mounted on a shaft 54.

Shaft 54 is journaled at its extremities in 85 bearings 55 attached to the upper extremities of substantially upright links 56. These latter have bolt and slot connections 57 with the frame of the run-out section of the apparatus, so as to permit of definite adjustment vertically of said shaft 54 with respect to this section and more especially to permit the paper-engaging sides of these belts to be bent down slightly around the pulleys 58, of which there are two as shown 90 in Fig. 3, and over which pulleys pass the underneath or co-acting angle-belts 59, which receive the papers from the belts 30—30'.

The upper ends of the links 56 are connected by the ends of the shaft 54 to the outer ends of links 60, the inner ends of which are pivoted at 61 to plates 62 which are attached to the upper ends of the channels 22.

The shaft 52 is journaled in the respective free ends of arms 63, which as shown in Fig. 1 are pivotally attached at their lower ends to plates 64 by means of a shaft 65.

The two belts 59 above referred to, each 110 pass around but two pulleys, one of these being designated 58 as above noted and the other being the corresponding pulley 66. The pulleys 58 are mounted on shafts 67 while the pulleys 66 are mounted on the 115 shaft 33 which carries the pulleys 32 above referred to.

On this shaft 67 are also three pulleys 68 around which pass the respective horizontal delivery belts 69, the upper or paper-carrying sides of which are supported on one or more rolls 70—70', as shown in Fig. 1, while the under sides of said belts rest on idler rolls 71.

The rolls 70 and 71 are journaled in suitable brackets carried by the horizontal members 71' which extend to the point where the papers are to be delivered from the endless belts 69, in a known manner.

The shaft 5 is driven clockwise, as viewed 130

in Fig. 1, by the chains 7 and sprockets 6, as above described, and a sprocket 72 of the same size as the sprocket 6, is connected by a chain 73 with a sprocket 74 mounted on a 5 shaft 75, which as shown in Fig. 2 has keyed or otherwise secured thereto a bevel gear 76. This gear is in mesh with a similar gear 77 mounted on a spindle or shaft 78, which like the shaft 75 is journaled in the 10 bracket 79 which lies in the obtusely angled portion of the band 21. The gears 76, 77 for clearness have been omitted in the small scale drawing of the apparatus shown in Fig. 1; but the sprocket 75 and a corresponding sprocket 80 have been indicated in 15 said figure in dash and dotted lines to show the chain connections.

As shown in Fig. 2, the sprocket 80 is mounted upon the spindle of shaft 78 and of 20 course is driven at the same speed as the sprocket 74, since the bevel gears which connect these spindles 75 and 78 are of the same pitch diameters.

A chain 81 connects the sprocket 80 with 25 a sprocket 82, which as shown in Fig. 3 rides on the shaft 67. Upon the outer end of this shaft is a spur gear 83 which is in mesh with a gear 84, mounted upon the corresponding end of the shaft 37. Gear 84 is 30 also in mesh with a narrow faced gear 85, similar to the gear 83; gear 85 being fast to the end of the shaft 33. As a result of these gear connections, the shafts 37, 33 and 67 will of course all be driven at the same 35 speed.

Aside from the sprocket and chain connection leading up from the shaft 5, as above described, it is evident that the belts 30—30' will tend to drive the shafts 33 and 40 37 at the same speed; but it is desirable to relieve these belts from any special tension other than that provided by their respective tensioning devices, so that it is preferable to use the chain and sprocket connections and gears to the end that slippage 45 between the ascending runs of the belts 30 and 30' may be substantially eliminated.

The tension upon the angle belts 49 is 50 preferably quite light and in practice the weight of the pulleys 51, shaft 52, and arms 63 has been found sufficient since the weight of these parts tends to rock the shaft 52 clockwise around its pivotal axis, as viewed in Fig. 1.

55 The operation of the conveyer will now be briefly considered.

Papers delivered by the fly 10 to the horizontal belts 1 are carried in overlapped relationship toward the angle belt 11 which 60 changes their direction of movement smoothly and with but little tendency to smear the freshly printed papers, preparatory to delivering them between the ascending limbs of the elevating belts 30—30'. 65 These belts receive the papers between their

projection-free faces and carry them up in their overlapped relationship past the guide and tensioning rollers 28.

Since during their ascent these papers are to be rotated clockwise, as viewed in Fig. 2, 70 through an angle which may be 45° or more, there is a tendency for the several belts in each set of the same, such as those designated 30 or those designated 30', to approach each other during the first half of 75 their ascent, and thereafter to correspondingly separate from each other during the last half of the ascent. This is due to the fact that the belts are under tension and hence tend to straighten out, while since a 80 straight line is the shortest distance between two points, the rotation of the upper shaft through, for example, 45° with respect to the lower shaft of a given set of belts, tends to cause the two outermost belts of a set of 85 three, to approach most nearly the middle belt of the set, half-way up between said shafts. To make this action more clear, let us assume that the shaft 33 be rotated, not through 45° with respect to the shaft 5, as in the 90 present case, but through 180°. In such a case, the two outer belts 30' would actually cross and make contact with each other half way between the planes in which lie said shafts 5 and 37.

Now this tendency for each set of belts to narrow up in their overall width as they depart from the shaft 5, for example, until they reach a plane midway between those in which lie the shafts 5 and 37, and to thereafter again separate from each other or widen out in their overall width as they approach their respective upper pulleys, is rather disastrous to freshly printed newspapers or the like, if such tendency be not counteracted; 100 since during the first half of the upward movement, the outer belt in each set tends to wipe across the surface of the overlapped newspapers and smear the ink, or said papers may be rumpled up or wiped over 110 each other with equally bad results.

By providing guiding projections such as those designated 31, or the equivalent thereof, upon one side of each of these belts, and by causing these projections to ride in 115 grooves in the guiding and pressure pulleys 28, this tendency for the belts 30 (and correspondingly 30') to thus play laterally toward and from each other, is substantially obviated; since the spacing between the 120 grooves 28' is constant for all rollers 28 and these rollers are set relatively close together. Obviously, if the twist is greatly in excess of 45°, these rollers would correspondingly be set closer together than they have been 125 shown; but it has been found in practice that for a twist such as that given by way of exemplification, the vertical spacing between the rollers as indicated in Fig. 1, gives excellent results.

It will be understood that alternate rollers will engage, for example, a given belt 30, while the intermediate alternate rollers will correspondingly engage the apposed belt 30', and that these rollers are so staggered with respect to each other as to afford the requisite grip of the apposed belt portions upon the papers to prevent the latter from slipping downwardly either with respect to each other or with respect to the belts between which they are being carried.

The grooved rollers 28 therefore perform a plurality of functions in that they not only serve to supply the requisite lateral pressure at spaced intervals whereby to grip the papers between the belts; but further they serve to maintain a proper spacing between the belts of each set and further serve to prevent lateral vibratory motion of these belts which also would tend to smear the freshly printed papers.

While, especially for short lifts, it is possible to use other than flat belts for the conveyance of the papers from one level to another while rotating said papers angularly during their translation, I greatly prefer to use narrow flat belts such as I have shown, and to provide upon the non-paper-engaging sides of these belts, such projections as those designated 31, which are preferably narrower than the width of the belt to which they are attached; while furthermore these projections are shaped and mounted with respect to each other so as to permit the belts 30 to turn freely around pulleys of relatively small radius.

To resume the description of the operation of my improved conveyer, it will be understood of course that the tensioning devices co-act with the belts 30-30' to maintain in these latter sufficient tension to prevent any downward slippage of the articles being carried thereby, so that the latter will be carried up smoothly and with unimpaired surfaces until they are delivered between the angle belts 49 and 59, of which as noted there are two of each; those designated 59 supporting the papers while the belts 49 apply the requisite pressure upon said papers to prevent them from slipping with respect to each other until they have passed out from between said belts 49 and 59, onto the horizontal delivery belt 69.

In connection with this delivery of the papers to said horizontal belts, I regard the provision of means whereby the upper and forward pulleys 53 of the angle belts 49, may be adjusted vertically with respect to the pulleys 58, which slightly deflects the under sides of these angle belts, as of considerable importance; since in order to secure the best results, the relationship between these pulleys should be quite nicely determined.

Finally, I desire to direct particular attention to the novel frame construction em-

ployed, which admirably adapts itself to any desired conditions and affords substantially any desired angular displacement or twist of the top of the conveyer with respect to the lower end thereof; while the mounting of the roller bearings upon arcuate supports greatly favors the proper adjustment of the rollers with respect to the elevating belt, before these bearings are finally clamped or otherwise secured in place. There is obviously a valuable relationship between these arcuate bearing supports and the self-aligning journals which are mounted in the bearings carried by said supports; since owing to the progressive twisting, step by step, in the belts of a given set, it would be very difficult at times to properly mount the rollers while preserving the advantage of being able to adjust the support therefor during erection.

By the term apposed belts as used in certain of the claims, I refer to belts such as those designated 30 and 30', or the equivalent thereof either in shape or disposition with respect to each other.

Similarly, where, in said claims, it is specified that the pressure rolls are disposed in staggered relationship alternately on opposite sides of the conveying portions of the twisted belts 30-30', such phraseology is to be considered as sufficiently comprehensive to cover obvious equivalents for such dispositions of the pressure rolls 28 as have been given merely by way of exemplification in the construction illustrated, since it is clearly unessential that every successive pressure roll should exactly alternate with the roll next below it.

Having thus described my invention, what I claim is:

1. Apparatus for conveying newspapers and the like having therein means for moving the objects conveyed at different levels respectively in different directions, and means for taking the objects from one of said levels to another comprising a series of opposed pairs of endless belts adapted to grasp the articles between opposed runs thereof, means for guiding the series of belts at different levels in planes at different angles, and means coacting with the belts at a plurality of such levels there to maintain the respective pairs of belts at substantially like distances apart, whereby to prevent relative crowding together of the said pairs of belts with respect to each other and the objects conveyed during rotation of the plane of the series of belts and of the objects conveyed.

2. A conveyer for newspapers and the like having therein an elevator section comprising a plurality of pairs of opposed belts, guiding means for the belts adapted to cause the series of belts to twist to different angular positions at different levels, and

means to maintain the same spacing apart in a horizontal sense between the respective pairs of belts at the different levels, whereby to prevent the respective belts from wiping across the surfaces of objects carried between the members of the opposed pairs of belts.

3. In apparatus for conveying newspapers and the like, the combination of a 10 twist-frame extending between two levels from one to the other of which articles are to be carried, said frame comprising a lower set of uprights and an upper set of uprights out of alinement with the lower set, connections between said sets of uprights to permit of initial adjustment of the upper set rotarily about the conveyer axis with respect to the lower set, sets of endless belts mounted in said frame and having apposed 15 sides for carrying said articles between said levels, means to deliver said articles to said belts at one of said levels, said delivering means translating said articles along a determined path, means to receive said articles 20 from said belts at the other of said levels and to convey said articles along another path which extends angularly with respect to said first mentioned path, means to cause said belts to rotate said articles about their 25 line of translation considered as an axis, during their movement between said levels, the amount of angular movement of said articles being substantially in correspondence with the angular departure of said 30 second path from parallelism with said first path, and means to prevent the respective belts in each set of the same from wiping across the surfaces of the articles carried thereby as they rotate said articles during 35 40 transit as aforesaid.

4. In apparatus for conveying newspapers and the like, the combination of a twist-frame extending between two levels from one to the other of which articles are 45 to be carried, said frame comprising a lower set of uprights and an upper set of uprights out of alinement with the lower set, connections between said sets of uprights to permit of initial adjustment of the upper set 50 rotarily about the conveyer axis with respect to the lower set, sets of endless belts mounted in said frame and having apposed sides for carrying said articles between said levels, means to deliver said articles to said 55 belts at one of said levels, said delivering means translating said articles along a determined path, means to receive said articles from said belts at the other of said levels and to convey said articles along another 60 path which extends angularly with respect to said first mentioned path, pressure and guide rolls to cause said belts to rotate said articles about their line of translation considered as an axis, during their movement 65 between said levels, swiveled bearings for

said rolls, supports for and to co-act with said bearings to permit of initial adjustment of said rolls angularly with respect to each other, and means to prevent the respective belts in each set of the same from wiping across the surfaces of the articles carried thereby as they rotate said articles during 70 transit as aforesaid.

5. In apparatus for conveying newspapers and the like, the combination of a 75 frame comprising elongated members and roller-bearing supports, swiveled roller-bearings mounted on said supports, pressure rolls mounted in said bearings, apposed twisted conveying belts mounted in said 80 frame, said rolls and their bearings being successively adjusted in correspondence with the twist of said belts and said supports projecting laterally with respect to said elongated members to accommodate 85 said adjustment.

6. In apparatus for conveying newspapers and the like, the combination of a frame comprising elongated members and arcuate roller-bearing supports, swiveled 90 roller-bearings mounted on said supports, pressure rolls mounted in said bearings, apposed twisted conveying belts mounted in said frame, said rolls and their bearings being successively adjusted in correspondence 95 with the twist of said belts and said supports projecting arcuately with respect to said elongated members to accommodate such adjustment.

7. In apparatus for conveying news- 100 papers and the like, the combination of a frame comprising two sets of elongated members with arcuately formed connections therebetween to accommodate initial rotary adjustment of one of said sets with respect 105 to the other about the axis of said frame, apposed twisted conveyer belts mounted in said frame, bearings carried by said frame, and pressure rolls disposed in staggered relationship alternately on opposite sides of 110 the conveying portions of said belts and mounted in said bearings, successive rolls on a given side of said belt portions having their axes angularly disposed with respect 115 to each other substantially in correspondence with the twist in the portions of said belts extending between them.

8. In apparatus for conveying newspapers and the like, the combination of a frame comprising two sets of elongated members 120 with connections therebetween to accommodate initial rotary adjustment of one of said sets with respect to the other about the axis of said frame, apposed twisted conveyer belts mounted in said frame, bearings carried by said frame, and pressure rolls disposed in staggered relationship alternately 125 on opposite sides of the conveying portions of said belts and mounted in said bearings, successive rolls on a given side of said belt 130

portions having their axes angularly disposed with respect to each other substantially in correspondence with the twist in the portions of said belts extending between them.

9. In apparatus for conveying newspapers and the like, the combination of a frame, apposed twisted conveying belts mounted on said frame, pressure rolls disposed in staggered relationship alternately on opposite sides of the conveying portions of said twisted belts, successive rolls on a given side of said belt portions having their axes angularly disposed with respect to each other substantially in correspondence with the twist in the portions of said belts extending between them, and mountings for said rollers carried by said frame and adjustable with respect thereto to accommodate the axes of said rollers to the twist in said portions.

10. In apparatus for conveying newspapers and the like, the combination of a substantially vertical frame, sets of apposed twisted conveying belts mounted in said frame to carry newspapers up from a lower to a higher level, pressure rolls disposed in staggered relationship alternately on opposite sides of the conveying portions of

said twisted belts, angle belts to receive the newspapers from said twisted belts, and means to adjust the angle of the delivery ends of said angle belts with respect to the general line of travel of the newspapers as the latter approach said angle belts.

11. In apparatus for conveying newspapers and the like, the combination of a substantially vertical frame, sets of apposed twisted conveying belts mounted in said frame to carry newspapers from one level to another, pressure and guide members adapted to maintain the spacing of said sets of belts disposed in staggered relationship alternately on opposite sides of the conveying portions of said twisted belts, angle belts to receive the newspapers from said twisted belts, and means to adjust the angle of the delivery ends of said angle belts with respect to the general line of travel of the newspapers as the latter approach said angle belts.

In testimony whereof I have affixed my signature in the presence of two witnesses.

CHESTER S. JENNINGS.
